UNITED STATES PATENT OFFICE.

FRIEDRICH NAUSS, OF VIENNA, AUSTRIA.

KNIFE-EDGE BEARING FOR WEIGHING APPARATUS.

Application filed April 14, 1927, Serial No. 183,859, and in Austria May 11, 1926.

The present invention relates to an improved knife edge bearing for use in weighing apparatus or balances.

In the usual types of bearings having 5 knife edges resting in a V-bearing the two halves of which are separated from one another, the essential condition that the two inclined surfaces forming the V-bearing should be in true lineal contact with the corresponding knife edge over the whole of the 10 contacting surface of the V-bearing can be adequately fulfilled by the employment of modern grinding methods.

If, however, the two inclined seating 15 members the surfaces of which form the V-bearing, are constructed of special material which has to be fitted into the bearing block, the aforementioned condition with regard to the true lineal contact between the knife 20 edge and the V-bearing is not easily realizable without making it necessary to grind said V-bearings after they have been fitted in.

The object of the present invention is to 25 provide a bearing of the aforementioned type, in which the true lineal contact between the knife edge and the V-bearing is automatically ensured, this end being attained by mounting the two inclined separated seating members in such manner that 30 they are capable of swinging or turning movement as hereinafter set forth.

One constructional form of the invention is illustrated by way of example in the accompanying drawings, in which:

Fig. 1 shows diagrammatically a side view of a device according to the invention in section through the knife edge and the V-bearing.

Fig. 2 shows on the left hand side a front elevation of the knife edge and a section through the V-bearing taken in the longitudinal direction of the knife edge, and on the right hand side, an elevation of the V-bearing.

Figs. 3 and 4 show details of the device.

Referring to the drawings, the bearing comprises two seating surfaces E and E' which are ground flat and which are arranged so that they do not directly intersect one another inasmuch as they are located on different parallel vertical planes, but they are so arranged that their projections on to a vertical plane parallel to their planes would intersect one another. They are thus arranged with regard to one another in

somewhat similar manner to the blades of a pair of scissors. The device is constructed in such a manner that the contact between the knife edge S and the seating surfaces 60 automatically adjusts itself so as always to be truly lineal.

With this object in view the two ground seating members, which may be made of steel or of the usual stone, such as agate, are 65 mounted in saddles or saddle-like supports R and R₁, each of which rests on a bearing block B having inclined edges which lie at the desired angle with regard to one another.

The steel or stone seating members on which the seating surfaces E and E₁ are ground, rest at their ends upon projecting points formed by recessing the sides of the bearing block B (see Fig. 4). In order to 75 prevent the possibility of the seating members falling out in transport, a pin C is also provided. The bearing blocks are screwed tight to the base U.

The possibility of longitudinal displacement of the knife edge taking place is prevented in the usual way by means of stop members A and A₁. The saddles R and R₁ (Fig. 3) consist preferably of sheet metal stampings and are each provided with a 80 suitable recess, the steel or stone seating members being fitted into said recess and cemented in place therein. The side supports for the seating members preferably consist of strips T and T₁ which are soldered on to the saddle and which project over a portion of the said recess. The saddles are adapted to swing to a slight extent around the edges of the bearing block B, the holes for the pin C not being adapted 85 to make a tight fit with the latter. In consequence of this the bearing automatically 90 adjusts itself in such manner that the contact between the knife-edge and the V-bearing 95 is truly lineal over the whole of the contacting surface of the V-bearing.

I claim:

1. A V-bearing comprising in combination: a bearing block having two oppositely inclined top edges; and seating members 105 turnably mounted on said edges, substantially as described.

2. A V-bearing comprising in combination: a bearing block having two oppositely inclined top edges; saddle-like supports 110 turnably mounted on said edges; and seating members having flat seating surfaces,

said seating members being fixedly mounted in said supports, substantially as described.

3. A V-bearing comprising in combination: a bearing block having two oppositely inclined top edges recessed in their middle portions; saddle-like supports mounted to rock upon said top edges and recessed in their middle portions; and seating members having flat seating surfaces, said seating members being fixedly mounted in the recesses of the said saddle-like supports, substantially as described.

4. A bearing block for a knife edge comprising in combination: a bearing-block, seating members having oppositely inclined surfaces mounted on said bearing block, and means for enabling said bearing members to turn about axes parallel to the oppositely inclined surfaces in such manner as to swing into true lineal contact with the knife edge, 15 substantially as described.

In testimony whereof I have affixed my signature.

ING. FRIEDRICH NAUSS.
